CLAIM

The ornamental design for a lid with square pattern and central hexagon element as shown and described.

DESCRIPTION

FIG. 1 is a top perspective view of a lid with square pattern and central hexagon element;

FIG. 2 is a bottom perspective view thereof;

FIG. 3 is a front elevational view thereof, a rear elevational view is not shown because it is a mirror image to the front elevational view;

FIG. 4 is a right-side elevational view thereof, a left-side elevational view is not shown because it is a mirror image to the right-side elevational view;

FIG. 5 is a top plan view thereof; and,

FIG. 6 is a bottom plan view thereof.

1 Claim, 5 Drawing Sheets
